UNITED STATES PATENT OFFICE

JOHN E. MUHLFELD, OF SCARSDALE, NEW YORK

BAFFLE WALL

Application filed January 18, 1923. Serial No. 247,536.

This invention relates to baffle walls, and more particularly to an improved baffle wall for locomotive fireboxes provided with one or more thermic siphons.

5 It is the primary object and purpose of my present invention to provide a baffle wall for fireboxes of the above type which is so mounted and arranged between the spaced siphons, the arch tubes and the side walls of the firebox as to provide a maximum combustion space between the grate and the arch at the forward end of the firebox and which will also effectively prevent the short circuiting of the flame or products of combustion to the 10 fire flues or tubes.

It is another object of the invention to provide an improved arrangement of the baffle wall in combination with one or more siphons which will permit of direct action of 15 the flame and radiant heat upon an extensive surface area of the siphon or siphons, thereby more rapidly promoting the generation of steam, resulting in increased boiler capacity and greater fuel economy than has heretofore been attained in the thermic siphon type of firebox.

With the above and other objects in view, the invention consists in the improved baffle wall, and in the form, construction and relative arrangement of its several parts as will be hereinafter more fully described, illustrated in the accompanying drawings, and subsequently incorporated in the subjoined claim.

35 In the drawings, wherein I have illustrated several simple and practical embodiments of my present improvements and in which similar reference characters designate corresponding parts throughout the several 40 views,—

Figure 1 is a longitudinal sectional view through a locomotive firebox illustrating one arrangement of the arch or baffle wall in combination with thermic siphons in the firebox and secondary combustion chamber;

45 Fig. 2 is a transverse sectional view taken substantially on the line 2—2 of Fig. 1;

Fig. 3 is a horizontal section taken on the line 3—3 of Fig. 1.

50 Referring in detail to the drawings, and

more particularly to Figs. 1 to 3 thereof, 5 designates the outer shell of the boiler, 6 the firebox, and 7 the crown sheet of the firebox. The secondary combustion chamber 8 extends forwardly of the firebox 6, and the walls of the firebox and said combustion chamber are spaced from the wall of the boiler shell 5 to provide the usual water circulating and steam generating space indicated at 9 of the required capacity.

The numeral 10 indicates the firebox grate, and above this grate one or more vertically disposed siphons indicated at 11 are arranged in the firebox, said siphons constituting auxiliary water legs and being of a well known construction. Each of the siphons, as herein shown is formed from heavy sheet metal having spaced side walls 12 connected at their lower edges by an obliquely inclined bulbous portion 13. The space between these side walls 12 of the siphon is in open communication through the crown sheet 7 with the water space 9, the upper edges of said side walls being welded or otherwise suitably secured to said crown sheet. The obliquely inclined bulbous lower portion 13 of the siphon is forwardly and downwardly extended in the form of a tube indicated at 14 which is connected with the water space 9 immediately above the forward end of the grate 10. In 50 the example illustrated by Figs. 1 and 2 of the drawings, I show two of the siphons 11, equidistantly spaced on opposite sides of the center line of the firebox. Between each siphon and the side wall of the firebox, an obliquely inclined arch tube 15 is arranged. The forward ends of these tubes are in communication through the wall of the secondary combustion chamber 8 with the water space 9. The rear ends of the tubes 15 are in communication with the rear vertical water leg.

Heretofore it has been the practice to arrange the baffle brick forming the arch in fireboxes of this type with their ends supported upon the lower bulbous portions 13 of the spaced siphons, or upon said portions of the siphons and supporting trunnions fixed to the side walls of the firebox and with the forward end of the arch in abutting contact against the throat sheet with which the 95 100

forward ends of the siphon tubes are connected. This throat sheet is indicated by the numeral 26 at the forward end of the grate 10. This prevents short circuiting of the flame and products of combustion, but in such case, the space between the fuel bed and the arch is entirely too limited in depth or volume either for proper combustion, or for practical purposes. At the forward end of 10 the fuel bed, ash, coal and clinker will accumulate until it reaches the under side of the arch. In order to level this portion of the fuel bed by means of the usual fire tools, it is practically impossible to avoid displacement of the arch brick from their proper positions and more or less serious damage thereto. I have succeeded in entirely obviating this objection by the baffle wall or arch arrangement illustrated in the drawings.

By reason of the firebox extension forming the secondary combustion chamber 8, I am enabled to build up the vertical baffle wall 16 of ordinary fire brick which is located immediately at the rear of the forward ends of the arch tubes 15. As shown, a single centrally located siphon 17 of generally similar construction to the siphons 11 extends vertically through the secondary combustion chamber 8 and the baffle wall 16 closely engages at its upper end with the rear obliquely inclined wall of this siphon.

Upon the opposite side walls 12 of each of the siphons 11, supporting studs or trunnions 18 are welded or otherwise secured in longitudinally spaced relation to each other. Similar supporting trunnions 19 or other suitable means of support are also secured to the opposite side walls of the firebox.

Preferably, I also provide the additional trunnions 18', 19' respectively, on the walls of the siphons and the furnace side walls which are adapted to engage over the upper faces of the brick forming the arch wall. 45 This is necessary, since it has been found in practice that when the locomotive is operating with a heavy exhaust which substantially increases the draft through the fire flues and tubes and the furnace there is frequently a tendency for the arch brick supported on the trunnions to be lifted up and become displaced from their proper positions on said trunnions and the arch tubes. The arrangement of the upper and lower trunnions 50 between which the brick ends are positioned effectually prevents this vertical lifting or displacement of the arch brick.

The baffle brick 20 constituting the horizontally inclined arch wall are supported 60 at one of their ends upon the trunnions 18 and 19. The brick between the siphons and the side walls of the firebox are suitably formed at their other ends for engagement with the upper sides of the arch tubes 15, 65 while the arch brick arranged between the

spaced siphons have their opposed ends provided with suitable means indicated at 21 so that these central arch brick are self supporting. The forward end of this inclined baffle wall abuts closely against the upper 70 end of the vertical wall 16 and thereby prevents any possibility of the short circuiting of the flames and products of combustion to the fire flues and tubes.

From reference to Fig. 1 of the drawings, it will be observed that by the above described arrangement of the inclined arch wall, greater combustion space is provided below the arch wall, particularly at the forward end of the firebox. The rearwardly extending portion of the arch wall is supported at a considerable distance above the lower bulbous portions 13 of the siphons, and it will therefore be evident that a considerable part of the surface area of each of the side walls 12 of the siphons will be subjected to the direct action of the flame and radiant heat of the fuel bed. In the baffle wall arrangements heretofore used, the evaporation surface of the siphons which represent auxiliary water 80 legs, with the exception of the lower bulbous part 13 thereof, was exposed only to the heat effects of secondary combustion and not at all to the direct action of the flame and radiant heat from the fuel bed. Thus, in the described arrangement, the generation of steam will be more rapidly promoted thus resulting in increased boiler capacity and greater economy in the consumption of fuel.

The described construction has been applied to and successfully tested on the Kansas City Southern Railway Mallet type of locomotive No. 766.

From the foregoing description considered in connection with the accompanying drawings it will be seen that I have devised a very simple form and arrangement of a baffle or arch wall for locomotive fireboxes of the thermic siphon type which is easily applicable to the conventional arrangement of the siphons, and necessitates no material alterations of any kind. Also the proposed new arrangement of the baffle or arch wall enables the fuel bed to be properly leveled without difficulty or damage to the arch brick, and greatly augments steam generating efficiency of locomotive fireboxes of this type while at the same time reducing operating costs.

In the foregoing description and in the drawings, I have referred to the adaptation of my present improvements in connection with two forms of thermic siphon fireboxes which are well known in the art. It is however, to be understood that the invention may also be employed in connection with firebox 125 constructions having a single siphon, or with three or more siphons, and either with or without the arch supporting tubes in addition to the siphons. It is accordingly to be understood, that in the various practical appli- 130

cations of the baffle or arch wall to different firebox constructions, in order to satisfactorily meet the requirements of the particular installation, I reserve the privilege of resorting to various structural changes both in the general combination and arrangement of the arch wall in connection with the siphons and in the details of form and construction of the individual arch brick, as may be fairly considered within the spirit and scope of the invention as claimed.

I claim:

In combination with a locomotive firebox having laterally spaced siphons therein opening through the crown sheet of the firebox and each provided with a lower obliquely inclined tubular extension opening through the throat sheet, and arch tubes extending through the firebox between the siphons and the side walls of the firebox; a vertically positioned baffle wall in advance of the siphons, and a horizontally inclined arch wall abutting the upper end of said vertical wall extending rearwardly therefrom, said arch wall consisting of baffle brick supported upon the arch tubes and trunnions fixed to the siphons and the side walls of the firebox, and extending rearwardly between the siphons and the firebox walls at a point intermediate the upper and lower parts of the siphons to thereby expose a maximum area of the siphon to the direct action of flame and radiant heat from the fuel bed.

In testimony that I claim the foregoing as my invention, I have signed my name hereto.

JOHN E. MUHLFELD.
